UNITED STATES PATENT OFFICE.

GEORGE T. BURROWS, OF CLEVELAND, OHIO, ASSIGNOR OF ONE-HALF TO E. H. GROENKE, OF LIMA, OHIO.

SAFETY LATHE DOG.

1,409,334.

Specification of Letters Patent. Patented Mar. 14, 1922.

Application filed August 9, 1920. Serial No. 402,423.

To all whom it may concern:

Be it known that I, GEORGE T. BURROWS, a citizen of the United States, and a resident of Cleveland, county of Cuyahoga and 5 State of Ohio, have invented a new and useful Improvement in Safety Lathe Dogs, of which the following is a specification, the principle of the invention being herein explained and the best mode in which I have 10 contemplated applying that principle, so as to distinguish it from other inventions.

The present invention relates to a lathe dog, and more particularly to the construction thereof, whereby a smooth exterior is 15 obtained, thus eliminating the liability of accidents due to the catching and tearing of the operator's clothing or hands by projections on the dog. Another feature, the arrangement of the operating parts whereby 20 they may quickly and readily be removed and replaced, if a breakage should occur. To the accomplishment of the foregoing and related ends, said invention, then, consists of the means hereinafter fully described and 25 particularly pointed out in the claims.

The annexed drawing and the following description set forth in detail certain mechanism embodying the invention, such disclosed means constituting, however, but one 30 of various mechanical forms in which the principle of the invention may be used.

In said annexed drawing:

Fig. 1 is a perspective view of my improved lathe-dog; Fig. 2 is an elevational 35 view of the driving side of the dog with the cover plate removed; and Fig. 3 is a sectional view on the line 3—3 of Fig. 2 but showing the cover plate in position.

The device consists of a cylindrical housing or spider 1, which is provided with a central hub 2, the housing being closed at the rear excepting for an aperture 3, and being cut away to form a series of arms or ribs 4, in order to lighten the housing. On 45 its outer surface 5 and communicating with one of the recesses 6 between the arms, the housing is provided with a slot 7. At one side the housing is left solid and from the hub a square recess 8 is cut into this solid 50 portion, this recess communicating with an aperture 9 extending the rest of the way through the housing. The housing is also provided adjacent its forward face with an annular flange 10 forming a shoulder 11 with the surface of the housing proper.

Opposite the square recess, the housing is provided with another solid portion having a rectangular recess or slot 12, which is also cut through the hub, and this recess is adapted to receive a removable jaw 13 which is 60 provided at its outer side with a curved recess 14 adapted to be in alignment with the aperture 3 in the face of the housing. A tail 15 having an eccentric portion 16, is adapted to fit in the curved recess 14 of the 65 jaw and to have a bearing in the aperture 3 within the housing. This tail extends out beyond the driving face of the housing and rotative movement of the same is adapted to cam the jaw inwardly, so that it extends 70 slightly beyond the hub in order to aid in gripping the stock when the lathe-dog is in operation. In the square recess 8 opposite the jaw, a standard square nut 20 is adapted to be removably mounted and held in place 75 by a screw 21 which is received in a tapped aperture 22 extending through the hub. Removably mounted through this nut is a set screw 23 which extends outwardly through the aperture in communication with the 80 square recess but the set screw is of such a length that it normally lies below the outer surface of the housing. This set screw is adapted to be forced into contact with the stock and to hold it securely against the jaw. 85

To enclose the casing so as to leave a smooth exterior with the exception of the extending tail, a movable ring 25 is mounted over the housing, the ring having two annular flanges 26, one of which fits against 90 the flange 10 on the housing so as to prevent the removal of the ring from the housing in one direction, while the other flange receives a cover plate 27 which fits flush within the ring. The cover plate is attached to the 95 housing by means of four screws 28 which engage with tapped apertures 29 in the arms of the housing. This cover plate is provided with a central aperture 30 of such size as to fit around the hub of the housing, and on its inner surface it is provided with a lug 31 fitting back of the end of the jaw, the lug being apertured to receive the tail and act as a bearing therefor. The ring has limited movement around the housing and is normally retained in one position by means of a spring 32. This ring is provided with a pin 33 which extends through the slot 7 in the housing into one of the recesses 6 between the arms. The spring 32 engages with 105

110

this pin and contacts with one of the arms to maintain the ring in its normal closed position. The ring is provided with a single aperture 33 having a rounded edge 34 which 5 aperture in one position of the ring is adapted to be an alignment in the aperture in the housing which receives the set screw, so that a wrench or other tool, may be inserted to tighten the set screw and force the stock 10 against the jaw. Upon removal of the wrench, the ring will be brought back to its normal closed position by means of the spring before mentioned.

It will be seen that the present lathe-dog 15 in its operative condition, is a substantially closed cylindrical housing having no projections nor protruding parts except the necessary tail for engagement with the face plate of the lathe. The opposite side has 20 no projections nor apertures with the exception of the one which receives and forms the bearing for the inner end of the tail. The driving side of the dog is entirely covered by the cover plate which carries four 25 screws for holding the plate in position, these screws as shown, being received in countersunk apertures, so that the screws are flush with or slightly below the surface of the plate.

30 As shown, each operative part of the dog is easily removable and those parts which are liable to breakage, such as the jaw, tail, set screw and nut, can be removed and replaced by merely taking off the cover plate 35 of the dog. The tail has a flattened side which is adapted to engage with the aperture of the face plate of the lathe in such a way, that the driving of the latter tends to rotate the tail and thus the eccentric, to force 40 the jaw inwardly against the stock. Thus the more power it takes to drive the stock, the tighter the stock will be held in the dog. The removal nut and set screw are standard 45 articles which may be purchased from any hardware store and while the jaw and tail must be made special, they are easily removable and can readily be supplied if breakage should occur. It will thus be clear that the housing is so formed as to eliminate 50 any danger to the operator and at the same time, the working parts are readily available so that in case of breakage, they can be removed and new parts substituted with a minimum of delay.

55 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

60 1. In a lathe-dog, the combination of a 65 cylindrical housing provided with a central

aperture and two opposed recesses in communication therewith, a removable jaw and operating tail mounted in one of such recesses, a removable set screw and nut mounted in the other of such recesses, a cover plate 70 removably attached to one face of said housing and a cylindrical ring fitting over said housing and making a flush surface with said housing and plate.

2. In a lathe-dog, the combination of a 75 cylindrical housing having a central aperture, one face being closed and the other face being hollowed out leaving a series of arms, two diametrically opposed recesses in such housing in communication with such central 80 opening, a removable jaw movably mounted in one such recess, a tail also rotatably mounted in such recess and operatively connected to said jaw to move the same upon rotation of said tail about its own axis, 85 a set screw and nut removably mounted in the other of such recesses, a cover plate for the open side of said housing, and a cylindrical ring adapted to fit over said housing and to make a flush surface with said housing 90 and said plate.

3. In a lathe-dog, the combination of a 95 cylindrical housing having a closed face and being hollowed out to leave a series of arms and recesses, said housing having a central aperture and provided with a hub on the open side of said housing, one of said arms having a square recess opening into said hub and an aperture through said arm to the exterior of said housing, the arm opposite 100 thereto having a rectangular recess, a nut removably mounted in such square recess, a set screw mounted in said nut and extending through such recess into such aperture, a jaw and tail removably mounted in said rectangular recess, said tail being rotatably mounted and being operatively connected to said 105 jaw to move the same inwardly upon rotation of said tail about said axis, a cover plate for such open side of said housing, and 110 a ring having an aperture movably mounted on said housing, said ring being normally held in closed position but being adapted to be moved to align such apertures in ring and housing to permit access to said set screw. 115

4. In a lathe-dog, the combination of a 120 cylindrical housing having a closed face and being hollowed out to leave a series of arms and recesses, said housing having a central aperture and provided with a hub on the open side of said housing, one of said arms having a square recess opening into said hub and an aperture through said arm to the exterior of said housing, the arm opposite 125 thereto having a rectangular recess, a nut removably mounted in such square recess into such aperture, a jaw and tail removably mounted in said rectangular recess, said tail being rotatably mounted and being operatively connected to said jaw to move said 130

- jaw upon rotation of said tail about its own axis, a cover plate for such open side of said casing said plate having an aperture adapted to fit over said hub and to form a flush 5 surface therewith, a ring movably mounted on said housing and provided with an aperture adapted to register in one position with the aperture in said housing to permit access to said set screw.
- 10 5. In a lathe-dog, the combination of a hollow cylindrical housing having one closed face, said housing having a central aperture and being provided with a hub and arms between said hub and the exterior surface, one 15 of said arms being provided with a square recess opening into such central aperture, and a communicating aperture through the exterior of said housing, a second arm opposite said first and provided with a rectangular 20 recess, a nut removably secured in such square recess, a set screw mounted on said nut, a removable apertured jaw mounted in said rectangular recess, a tail rotatably mounted in said rectangular recess and in such apertured jaw and being provided with 25 a cam face adapted to move said jaw upon rotation of said tail about its own axis, a ring mounted on said housing and having an aperture adapted in one position to be in alignment with such aperture in said housing to permit access to said set screw, a cover plate for said housing having a central aperture adapted to fit over said hub and make a flush surface therewith.

Signed by me this 4th day of August, 35
1920.

GEORGE T. BURROWS.
